No. 896,334.

PATENTED AUG. 18, 1908.

F. F. STOKES,
VENTILATOR.
APPLICATION FILED DEO. 7, 1907.

UNITED STATES PATENT OFFICE.

FRANCIS F. STOKES, OF NEW YORK, N. Y.

VENTILATOR.

No. 896,384.

Specification of Letters Patent.

Patented Aug. 18, 1908.

Application filed December 7, 1907. Serial No. 405,617.

To all whom it may concern:

Be it known that I, FRANCIS F. STOKES, a citizen of the United States, and a resident of the city of New York, borough of Brooklyn, county of Kings, and State of New York, have made a new and useful Improvement 5 in Ventilators, of which the following is a specification.

The object of this invention is to provide 10 a device of this class which can be inserted in sashes and which will enable the room to be ventilated without opening a window, or raising the sash. This object is accomplished by my invention, one embodiment 15 of which is hereinafter described.

For a more particular description of my invention, reference is to be had to the accompanying drawings forming a part hereof in which,

20 Figure 1 is a perspective view of a window provided with my improved ventilator. Fig. 2 is an end view of my ventilator applied to a window, a portion of the sash being shown. Fig. 3 is a sectional view 25 taken on the line 3—3 of Fig. 2, looking in the direction of the arrows. Fig. 4 is a sectional view taken on the line 4—4 of Fig. 3, looking in the direction of the arrows. Fig. 5 is a plan view of my improved ventilator 30 shown without the sash.

Throughout the various views of the drawings, similar reference characters designate similar parts.

My improved ventilator 1 is applied to the 35 frame 2 of a sash 3, and preferably the lower portion of the frame because it is more conveniently located and is larger than any other part of the sash. Where two sashes are employed, it is preferably applied to the 40 lower sash. In this frame 2 is made a cylindrical hole of any suitable diameter in which is set a metallic cylinder or bushing 4 which sets snug in said hole. The ends of this cylinder are preferably made flush with the exterior and interior surfaces of the frame 2, as shown in Fig. 3, and the exterior is preferably covered by a wire gauze 5, held in place by a perforated plate 6, which is fixed by 45 screws or other suitable means, as shown in dotted lines. The inner edge of this bushing 50 is slotted longitudinally for a short distance

so that lugs 7 may be bent inwardly therefrom for a purpose that will appear below.

A second bushing or cylinder 8 fits snug inside the bushing 4 with a sliding fit and at 55 its outer end this cylinder 8 is made open. Its upper wall is cut away at 9 to form an opening through which the lugs 7 pass. This opening 9 is preferably made rectangular in form with horizontally disposed edges by 60 which the lugs 7 are rubbed and the ends of this opening 9 may be made to have contact with the lugs 7 to limit the longitudinal movement of the bushing 9 in the cylinder 4. However, the preferred construction has the 65 inner end wall of the opening 9 where it is free and clear of the lugs 7 and the outer end wall of this opening impinges against these lugs so as to limit the movement of the bushing 8 in one direction. From the foregoing, 70 it is apparent that the lugs 7 prevent the bushing 8 from turning in the cylinder 4, and also limit its inward movement. Its outward movement is limited by a circular disk 10 fixed to the inner end of the bushing 8, and 75 symmetrically mounted on it. This disk 10 extends beyond the bushing 8 because it is of greater diameter and it is provided with two struck-up portions 11 which form finger holes so that the ventilator may be grasped 80 to draw it inward. This disk 10 is adapted to fit snug against the inner end of the cylinder 4 and the frame 3 so as to form a tight joint therewith.

When the ventilator is not used the bushing 8 is placed in the position shown in Fig. 3, and more or less of the opening 9 is exposed as desired, according to the amount of air admitted to the room. If one ventilator is not sufficient, it may be duplicated indefinitely provided the capacity of the sash is not exceeded. The ventilator is closed from the position shown in Fig. 3, by shoving the bushing 8 outwardly, as is obvious.

Other embodiments of my invention may be made which employ its substance, but as its scope is set forth in the annexed claims, further description is unnecessary.

What I claim is:—

In an article of the class described, an 100 outer cylindrical bushing, a gauze covering one end of said bushing, inwardly extending

23
lugs on said bushing integral therewith, an inner bushing suitably mounted in said outer bushing having one end closed by a flanged disk and its other end open and a circumferential opening in the cylindrical wall of said inner bushing, through which the lugs protrude to limit the movements of said inner bushing within the outer bushing, the

flange of the disk being in line with the end of the outer bushing.

10

Signed this 7th day of November, 1907.

FRANCIS F. STOKES.
